UNITED STATES PATENT OFFICE

SOPHIA SOLOMON, OF BROOKLYN, NEW YORK, ASSIGNOR TO JOSEPH BERLINGER COMPANY, OF NEW YORK, N. Y., A CORPORATION OF NEW YORK

DESIGN FOR A TEXTILE FABRIC

Application filed December 3, 1932. Serial No. 46,288. Term of patent 3½ years.

To all whom it may concern:

Be it known that I, SOPHIA SOLOMON, a citizen of the United States, residing at the borough of Brooklyn, in the county of Kings and State of New York, have invented a new, original, and ornamental Design for a Textile Fabric, of which the following is a specification, reference being had to the accompanying drawing, forming part thereof.

The figure is a plan view of a textile fabric, intended for a square scarf, showing my new design. A quarter section of my design is substantially comprised within the area defined by the indicating lines shown on the drawing.

I claim:

The ornamental design for a textile fabric, substantially as shown and described.

SOPHIA SOLOMON.
